BULLET EXTRACTOR FOR CARTRIDGES

Anthony Andrade, Santa Clara, Calif.

Application September 29, 1953, Serial No. 382,903

3 Claims. (Cl. 86—23)

The present invention relates to ammunition and pertains more particularly to a device for extracting the bullets from the cartridge cases of small arms ammunition.

It is frequently necessary with military ammunition, particularly in the 30-06 and 50 calibers to withdraw the bullets from the cartridge cases in order to salvage for re-use the component parts of rejected or damaged ammunition. There are also a large number of rifle and pistol shooters who hand-load their own ammunition, and such hand loading frequently requires the withdrawal of the projectiles either from factory loaded ammunition or from other ammunition which the rifleman may wish to disassemble for one reason or another.

It is important in the extracting of bullets from their cartridge cases that the bullets and cartridge cases be seized in a manner which will prevent injury to either thereof. For this reason, it is desirable that the cartridge case holder and the bullet gripping means be positioned accurately for each withdrawing operation of the mechanism. Even a slight misplacement of the bullet gripping means may result in damage either to the bullet or to the neck of the cartridge case.

It is the general broad object of the present invention to provide an improved bullet puller for extracting the bullets from the cartridge cases of assembled ammunition. The invention also contemplates the accurate positioning of a bullet seizing member for axially withdrawing a cartridge case from a bullet mounted therein. The invention also provides an axially adjustable bullet gripping device for mounting on one of a pair of separable members of a bullet pulling machine, the other of said separable elements being provided with means for gripping the rim of the cartridge case.

These and other objects and advantages of the invention will be brought out more fully in the following description and the accompanying drawings, wherein:

Fig. 1 is a perspective view of a bullet puller embodying the present invention.

Fig. 2 is a longitudinal sectional view through the mechanism shown in Fig. 1, portions of a supporting machine being indicated in broken lines, as is also a cartridge inserted in the device for disassembly.

The illustrated form of the invention comprises a bullet puller A having generally tubular support housing 10, which may be of steel. The housing 10 has an externally threaded lower portion 11 of reduced diameter. The threaded lower housing portion 11 is screwed into a threaded hole 12 provided therefor in the uppermost member 13 of a supporting mechanism consisting, as far as the present invention is concerned, of the two separable members 13 and 14. These members are controlled for separation by mechanism of a conventional type (not shown) to move them selectively a predetermined distance toward and away from each other in a direction axially of the threaded hole 12 into which the housing 10 is screwed. A lock nut 15 is provided to se-

2

cure the housing 10 in axially adjusted position in the machine member 13.

A pair of undercut cartridge case gripping members 17, 17 are secured by screws 17a to the machine member 14 in a position to receive the rim 18 of a cartridge case 19 therein. Thus, when the machine members 13 and 14 are separated, the cartridge casing 19 will be withdrawn from the bore 30 of the housing 10.

The bore 30 is of a size to receive freely therein a cartridge casing 19 (Fig. 2) of the maximum size to be handled by the device A. A flange 31 of increased diameter is provided around the upper end of the threaded lower housing portion 11, and a pair of support standards 32, 32 are formed integrally with the threaded lower housing portion 11 to extend vertically upwardly from diametrically opposite sides of the flange 31.

A tubular upper housing portion 33 is mounted integrally on the standards 32, 32 with its bore 34 disposed coaxially with that of the threaded lower portion 11. A headed sleeve 37 is fitted telescopically into the top of the upper housing portion 33. The enlarged head 38 of the sleeve 37 seats upon the upper edge of the cylindrical upper housing portion 33 to prevent downward displacement of the sleeve 37 relative to the housing 10.

The sleeve 37 is secured against rotation in its fully seated position in the housing 10 by a set screw 39. The head portion 38 of the sleeve 37 has a hole 40 axially therethrough to journal a chuck control screw 41 therein. The chuck control screw 41 has an enlarged head portion 42 thereon, and a turning pin 43 is inserted in a hole provided therefor transversely of the axis of the screw 41. The head portion 42 of the chuck screw 41 is supported on a washer 44 which preferably is of friction reducing material such as brass or bronze. The washer 44 rests on the head 42 of the sleeve 37.

The threaded chuck control screw 41 is screwed into an internally threaded upper bore portion 45 provided therefor in a collet type chuck member 47 which is fitted for axial sliding movement into the lower end of the bore 48 of the headed sleeve 37. The lower end of the chuck 47 is divided by longitudinally extending slits 49 into a plurality of symmetrical fingerlike jaws 50 in a manner customary in the making of collet chucks. The bore 51 of the lower end portion of the chuck 47 is smooth, and is of a size to receive therein a bullet 52 of the size to be removed. The external faces of the four finger-like jaws 50 of the collet chuck 47 are of slightly increased diameter at their lower ends 53, as is common in the making of collet chucks, so that as the chuck 47 is drawn upwardly into the sleeve 37 by rotation of the chuck control screw 41 the jaws 50 will grip the bullet 52 of a cartridge B inserted therein.

A chuck positioning pin 54 is fitted with a close press fit into a hole provided therefor in the side of one of the standards 32 at a height to support the collet chuck 47 in a desired position to receive the bullet 52 a required distance therein. If desired, a pin 54 may be secured in position in the housing 10 by brazing or silver soldering. The pin 54 is mounted with its axis disposed radially to the axis of the upper housing portion 33 and extends inwardly from its supporting standard 32 a sufficient distance to extend beneath the collet 37, but not sufficiently to contact a cartridge B positioned with its bullet 52 inserted co-axially in the collet.

In using the bullet puller A of the present invention, a collet chuck member 47 is selected having a desired internal diameter to receive and grip a bullet 52 of the size to be extracted. The device A is mounted by screwing the threaded lower housing portion 11 into the threaded opening 12 in the member 13, as shown in Fig. 2.

When it is necessary to change collet chucks 47, this may be accomplished by unscrewing the set screw 39 to free the headed sleeve 37, removing this sleeve 37 with the chuck 47 and chuck control screw 41 therein, unscrewing the screw 41 to release the chuck 47. The chuck 47 then is replaced with another generally similar chuck (not shown) having the required bullet receiving bore diameter. The parts are then reassembled by reversing the above procedure.

The rim receiving tracks 17, 17 should be of a size to receive and overlie the rim 18 of the cartridge to be disassembled. If necessary the tracks 17, 17 may be removed by unscrewing the screws 17a and replaced with tracks of the proper size and amount of separation such replacement tracks (not shown) may be secured in position by replacing the screws 17a, 17a.

For adjusting the device preparatory to an actual bullet extracting operation, the collet control screw 41 is unscrewed sufficiently to free the flared lower end portions 53 of the collet jaw members 50 from the sleeve 37 and thus to permit the chuck 47 to rest on the chuck positioning pin 54. A cartridge B of the size to be disassembled then is inserted in the device A as shown in Fig. 2 with the machine members 13 and 14 in their fully shut or closed position of minimum separation substantially as shown in Fig. 2. The housing 10 is screwed into or out of the machine member 13 as required to bring the cartridge into position where the chuck 47 will grip the bullet 52 as close to the top of the cartridge case 19 as possible but will not nip the neck 19a of the cartridge case. This adjustment is easily observed by looking in between the standards 32, 32. When the proper adjustment is attained the housing 10 is secured in adjusted position by means of the lock nut 15.

The cartridges then may be disassembled by inserting the rim 18 in the tracks 17, 17 as shown in Fig. 2 with the machine members 13 and 14 in their open or separated condition (not shown), the cartridge B axially aligned with the housing bore 30, and the chuck 47 freed to rest upon the chuck positioning pin 54.

The machine members 13 and 14 then are moved to their closed position shown in Fig. 2, and the chuck control screw is turned to draw the chuck 47 into the sleeve 37 to grip the bullet 52. The machine members 13 and 14 then are separated axially of the cartridge B to withdraw the bullet 52 from the cartridge casing 19 and to withdraw the cartridge casing 19 from the bore 30 of the housing 10. The chuck 47 then is released by unscrewing the chuck control screw 41, which permits the bullet to drop through the bore 30 and upon removal of the cartridge casing 19, places the apparatus in condition to repeat the operation.

While I have illustrated and described a preferred embodiment of the present invention, it will be understood however, that various changes and modifications may be made in the invention as set forth in the appended claims.

Having thus described the invention, what I claim as new and desire to protect by Letters Patent is defined in the following claims.

I claim:

1. A bullet extractor for mounting on one of a pair of machine members constructed and arranged to move selectively toward and away from each other along a straight path, one of said machine members having a threaded hole therethrough, the other of said machine members being formed to grip the base of a cartridge with the cartridge axially centered in the hole in said one machine member; said extractor comprising a housing having a first tubular end portion threaded externally for threaded insertion in the threaded hole in said one machine member, a pair of standards extending from said

tubular housing oppositely from said base gripping machine member, said standards being on opposite sides of the bore axis of said housing portion, a second tubular housing portion mounted on the outer ends of said standards co-axially of said first housing portion, a sleeve fitted co-axially into the outer end of said outer housing portion, a flange on the outer end of said sleeve seated on the outer end of said second housing portion to support the sleeve in axially spaced relation to said first tubular housing end portion, a collet chuck of a predetermined size fitted into said sleeve, with its end nearest the base gripping member visible between said standards, a screw having a portion thereof seated on the outer end of said sleeve and threadedly engaging said collet chuck for drawing the chuck axially into the sleeve to tighten the chuck, and a chuck stop fixedly mounted on one of said standards and positioned to limit movement of the chuck toward the base gripping member to adjusted position clear of the neck of a cartridge case visible, together with the lower end of the chuck, between said standards.

2. In a bullet extractor having a pair of machine members constructed and arranged to move relatively for a limited distance toward and away from each other, a first of said members having an element thereof formed to grip the case of a cartridge thereby to secure the latter in predetermined position; a chuck support member secured in adjusted position on the second of said machine members and having a sight opening in a side thereof, a chuck receiving sleeve on said chuck support member, a chuck of predetermined internal diameter mounted in said sleeve co-axially of a cartridge having its case gripped by said gripping element, the end of said chuck nearest the case gripping element being exposed in said sight opening, a chuck actuating screw having a portion thereof rotatively seated on said sleeve and threadedly engaging said chuck for drawing the chuck axially of the sleeve to tighten the chuck on the bullet of a cartridge having its case gripped by said gripping element, and a chuck stop fixedly mounted on said support member, and adjustable therewith, to limit movement of the chuck toward said case gripping element with the machine members at their limit of movement toward each other, to a position visible in the sight opening and clear of the neck of a cartridge having its case gripped by said gripping element.

3. In a bullet extractor having a pair of machine members constructed and arranged to move relatively for a limited distance toward and away from each other, a first of said members having an element thereof formed to grip the case of a cartridge and secure it in predetermined position, a chuck support member secured in adjusted position on the second of said machine members, a chuck of predetermined internal diameter mounted on said support member co-axially of a cartridge having its case gripped by said gripping element, the end of said chuck nearest the case gripping element being exposed to view laterally thereof, threaded chuck tightening means threadedly engaging said chuck for tightening the chuck on the bullet of a cartridge having its case gripped by said gripping element, and a chuck stop fixedly mounted on said support member, and adjustable therewith, to limit movement of the chuck toward said case gripping element, with the machine members at their limit movement toward each other, to a position visible laterally thereof and clear of the neck of a cartridge having its case gripped by said gripping element.
